Primary Examiner — Elizabeth A Albert(74) *Attorney, Agent, or Firm* — Kyle Fletcher**CLAIM**

The ornamental design for a wine cork paperweight, as shown and described.

DESCRIPTION

FIG. 1 is a front view of a wine cork paperweight.

FIG. 2 is a side view of the claimed design.

FIG. 3 is a top view of the claimed design.

FIG. 4 is a bottom view of the claimed design; and,

FIG. 5 is an isometric view of the claimed design.

The words "LABEL" ad "PORTER CREEK" appearing in FIGS. 4-5 are environmental matter and form no part of the claimed design.
